UNITED STATES PATENT OFFICE.

RUDOLF BUNGEROTH, OF DUSSELDORF, GERMANY.

TUBE EXPANDER.

Application filed July 23, 1927, Serial No. 208,013, and in Germany December 29, 1925.

The invention relates to apparatus for expanding metal tubes with regular or varying thickness of wall.

The expanding of tubes by inclined roller devices by the use of a mandrel has been several times attempted. The arrangements hitherto preferably used, in which the mandrel-shafts are subjected to pressure, have given rise to considerable difficulties since 10 the mandrel subjected to pressure, yields more or less in accordance with the degree of the rolling pressure and accordingly alters its position relative to the rollers.

The result is an irregular and uncommercial manufacture.

It has also been proposed to secure the mandrel to a shaft placed at the inlet side of the machine whereby pressure on the mandrel or the mandrel shaft is avoided.

20 However, in these machines also it is not possible to realize the main condition for the production of a uniform product, which consists in maintaining the mandrel during the working period exactly in its position 25 between the rollers.

These defects of the known arrangements have been particularly noticeable in the manufacture of tubes of considerable length, as they are now generally required.

30 The present invention relates to machines in which the expanding is effected by means of a mandrel which is secured to a mandrel shaft placed on the inlet side of the machine and it is differentiated from the known apparatus in that the mandrel shaft is adjustably arranged.

In this manner, it is possible to maintain the mandrel always in a definite position between the rollers during the working 40 period, and consequently to compensate for any alteration of the mandrel shaft.

The adjusting means may be of any suitable kind and be arranged at either end of the mandrel shaft.

45 A coarse or fine adjustment of the mandrel may be provided. By the improved machine, the expanding of tubes of considerable length and constant dimensions presents no difficulties as the mandrel always maintains its definite position between 50 the rollers.

Figure 1 is a longitudinal section showing one form of the invention,

Fig. 2, is a longitudinal section through the mandrel controlling means in another 55 form of the invention in which a worm and worm-wheel is employed,

Fig. 3, is a longitudinal section through the mandrel controlling means in a third 60 form of the invention, wherein coarse adjustment is obtained as in Figure 1, and fine adjustment is obtained by means of an eccentric,

Fig. 4, is a detail of the eccentric shown in Fig. 3,

Fig. 5, is a longitudinal section through the mandrel controlling means in another form of the invention,

Fig. 6, is a fragmental view partly in section of the worm and worm-wheel employed 70 in Fig. 5,

Fig. 7, is a longitudinal section through the mandrel adjusting means in still another form of the invention, wherein coarse and fine adjustment are secured by means of a 75 differential screw,

Fig. 8, is a longitudinal section through a mandrel and adjusting means in which the mandrel adjustment is attained by means of 80 coacting parts carried at the mandrel end of the mandrel shaft, and

Fig. 9, is a longitudinal section through the mandrel controlling means in another form of the invention.

Figure 1 shows a disc apparatus in plan 85 in which roller discs *a*, which are relatively disposed in the known manner and, in conjunction with the mandrel *b*, effect the expansion of the tube. The mandrel shaft *c*, is, in this case, arranged on the entry side 90 of the apparatus. To one end thereof, is secured the mandrel *b*, its other end being connected to an adjusting device, which consists of a screw-spindle *d* and mounted thereon a nut *f*, provided with a hand-wheel *g*, 95 the said nut being rotatable but not axially movable in the frame *e*. With this construction, the mandrel shaft is not subjected to a bending but to a tensile stress. In this manner, even in the case of considerable 100 lengths which exceed that of the tube to be produced by about 1-2 metres a considerable reduction in the cross-sectional area of the mandrel shafts is effected, such shafts as hitherto used being subjected to pressure, and very heavy and therefore incon-

105

venient to handle. The mandrel shaft subjected to tension does not alter its length in proportion to the roller pressure and retains the mandrel in the adjusted position 5 under varying pressure.

The adjustment of the mandrel is made possible by the above described arrangement.

If a particularly fine adjustment of the mandrel is necessary, a worm-wheel, as 10 shown in Figure 2, can be employed in place of the hand-wheel *g*, the said worm-wheel being connected to the nut *f*, and rotated by a worm *i* actuated by hand or by means of a motor.

15 Figures 3 and 4 show a construction in which the coarse adjustment is again effected by the screw-spindle *d*, nut *f*, and hand-wheel *g*. For the fine adjustment an eccentric *k* is provided, which is turned by the 20 worm-wheel *i* and worm *m*.

In the construction shown in Figures 5 and 6, the adjustment is effected by levers *o*, pivoted to the frame at *n*, and engaging the 25 tension rods *p*. The rods *p*, are connected to a cross-head *q*, which is provided with an interior screw-thread but is prevented from turning by connection with the frame *e*, and in which screw-thread there engages a 30 sleeve *t*, which is exteriorly screw-threaded, is immovably secured to the frame *e*, and is provided with worm-teeth *r* engaging the worm *s*. A spring *u* holds the mandrel shaft housing *v*, constantly in proximity to the lever *o*, so that an unintended backward 35 movement of the mandrel shaft is avoided. The adjustment can also be effected by toggle levers or the like.

Figure 7 shows a construction in which the mandrel shaft *c*, is adjustable first by a 40 hollow screw-spindle *w*, provided with coarse threads by means of a worm-wheel *x*, and a worm *y*, and then by a second screw-spindle *z*, with fine threads mounted in the first spindle *w*. The rough adjustment of the 45 mandrel-shaft is effected by means of the first-spindle *w*, and the fine adjustment with the second spindle *z*.

50 In order to prevent the mandrel shaft taking part in the rotation of the mandrel during the working operation, which causes a considerable additional expenditure of power and disadvantageously affects the product, the mandrel is rotatable with the least possible friction on the mandrel shaft, so that 55 the latter is not rotated therewith. With mandrels, particularly those of greater diameter, the connection between mandrel and shaft can be effected by a sleeve on the outer surface of which is arranged the mandrel 60 and which, by means of pressure ball-bearings, transmits the mandrel pressure to the mandrel shaft. A cooling and lubrication of the ball-bearing can be effected either during each pause in the rolling, or if the 65 mandrel shaft be provided with a hole cool-

ing water can be conveyed to the bearing during the rolling operation.

The adjusting means may also, as Figure 8 shows, be arranged at that end of the mandrel-shaft on which the mandrel is situated. In the example shown, the adjustment is effected by a screw 1, and nut 2. Obviously, any other arrangement could also be used and also, a coarse and fine adjustment provided. Finally, the adjusting means can be arranged at each end of the mandrel-shaft.

80 Coarse adjustment may be made by fluid as illustrated in Fig. 9, but the use of fluid means is not specifically claimed herein.

By the displacement of the mandrel, the wall thickness can consequently be altered suitably even during the rolling operation. The mandrel can thus be designedly adjusted 85 during the working operation in order to obtain a tube of varying wall thickness at different parts and consequently, for example, to produce a tube with an alternately thickened or thin wall.

90 Alterations in the wall thickness can also be effected by the combined displacement of the mandrel and the rollers.

95 Claim to the method of producing a tube of varying wall thickness is not being made herein, but a division of the present application is being filed in which this method is being disclosed and claimed.

I claim:

1. In apparatus for expanding metal tubes, a mandrel shaft located at the inlet 100 side of the apparatus, and a mandrel carried by said shaft, in combination with means for giving rough adjustment to said mandrel and other means for giving fine adjustment to said mandrel.

2. In apparatus for expanding metal tubes, a nut rotatably mounted at the inlet 105 side of the apparatus and axially immovable, a screw spindle operated thereby, and a mandrel shaft connected to the end of the screw spindle, in combination with a mandrel carried by the mandrel shaft, rotation of said nut being adapted to displace axially said screw spindle and with it said 110 mandrel shaft, thereby adjusting said mandrel, and an eccentric and a worm and worm-wheel for operating the same, said eccentric being adapted to give fine adjustment to said mandrel.

3. In apparatus for expanding metal tubes, a mandrel shaft located at the inlet 115 side of the apparatus, and a mandrel carried by said shaft, in combination with screw means for giving rough adjustment to said mandrel, and other means for giving fine adjustment to said mandrel.

120 In testimony whereof I have signed my name to this specification.
